UNITED STATES PATENT OFFICE.

HARRY R. CHANDLER, OF KENNETT SQUARE, PENNSYLVANIA, ASSIGNOR TO THE GLACIFER CORPORATION, OF KENNETT SQUARE, PENNSYLVANIA, A CORPORATION OF DELAWARE.

SHIPPING CONTAINER.

Application filed March 9, 1928. Serial No. 260,476.

This invention relates to certain improvements in shipping containers and the like, but more specifically to the locking mechanism for the covers or closures of such containers; and the nature and objects of the invention will be readily recognized and understood by those skilled in the art in the light of the following explanations and detailed descriptions of the accompanying drawings illustrating what I at present consider to be the preferred embodiments or mechanical expressions of my invention from among various other forms, arrangements, combinations, and constructions of which the invention is capable within the spirit and the scope thereof.

In certain types of containers, and particularly those of the relatively large and heavy insulating types employed for transporting and shipping perishable goods and such like, it is essential that the removable covers or closures for such containers tightly seal the same and insulate the interior and contents thereof from temperature exchange, yet these closures must be readily quickly removable and replaceable for practical use and operation. Hence, it is a requirement with containers of this general type to provide a simple but strong and durable arrangement of mechanism for securing and attaching a closure or cover in tightly seated sealing relation on and with the container, which mechanism can be quickly and readily operated to release or detach a cover or closure, as well as to permit of quickly securing the same in container closing position, and which will stand up under the conditions encountered in use.

In a form of such cover or closure attaching mechanism in general use the cover carries a spring metal fastening pivotally mounted disposed diametrically across the cover and swingable to engage or disengage the structure of the container at opposite sides of the cover, to secure and release the cover to and from closing position on the container. In the handling of these containers in actual use they are stacked or piled one upon another, and it is found from actual experience that frequently in the operation of stacking and unstacking the same, the bottom or lower end of a container when drawn or slid across the cover closed top of the lower

container on which supported, will catch on and engage with the pivoted cover fastening member on the lower container cover and swing or rotate the same to cover released and opened position unsealing the container. This is a serious condition as it will result in the spoilage or ruining of the perishable materials in a container if undetected and not immediately remedied by refastening and securing the released cover in container closing and sealing position.

The present invention is directed to the elimination of this serious problem and hazard in the use of such cover attached and sealed containers, through the provision of an improved construction and arrangement of such type of cover attaching mechanism whereby the same is locked in position against accidental displacement and cover or closure release, while retaining for the mechanism those desirable characteristics of ease and rapidity of cover attaching and release, with simplicity in construction and durability in use.

A further object of the invention resides in the provision of certain improvements in the mounting and attaching of the pivotal cover fastening member on the cover, and in the construction of the container end structure engaged by such member whereby the locking thereof is obtained in a structurally simple and efficient manner.

With the foregoing general objects, and certain other objects and results in view, which other objects and results will be readily apparent from the following explanation, the invention consists in certain novel features in construction and in combinations and arrangements of parts, as will be more fully and particularly referred to and specified hereinafter.

Referring to the accompanying drawings: Fig. 1 is a vertical transverse section through the upper end of a container and cover embodying the cover attaching and locking mechanism of the invention.

Fig. 2, is a top plan view of a container and cover, with the cover attached and locked in closed position by the mechanism of the invention, the unlocked cover releasing position of the fastening member being shown in dotted lines.

Fig. 3, is a detail perspective view of a

portion of the container top or end ring with the fastening member receiving slot and locking lip or flange formed thereon.

Fig. 4, is a bottom plan view of the top or end ring with the fastener receiving slots and locking lips or flanges thereon.

The invention is disclosed herewith as embodied in a container of the insulated shipping type, in which the several problems and difficulties overcome by the invention are met with in a high degree, so that this type of container serves to more clearly illustrate and bring forth the several features of the invention. This form and type of container however is presented herewith by way of example only, as all features of the invention are not limited or restricted to use on or with such containers, but are applicable to other types and forms of containers where similar conditions are encountered, or where such use may be found desirable or expedient.

The container here shown in Figs. 1 and 2, it being deemed necessary for the purposes of this application to more or less diagrammatically disclose only the upper end portion of the container, is of the insulated type employed for transporting and shipping perishable materials, and embodies the container body 10, in the present example of cylindrical form although the invention is not limited to any form or shape of container, comprising or including any suitable or desired non-conducting insulating material. At the open upper end the container body includes the top or open end structure 11 providing the annular internal and depressed upwardly facing shoulder or seat 12 for receiving the cover or closure for the container.

This mouth or open upper end of the container is closed by any suitable cover or closure 20, in the present instance formed by any desired insulating material body or plug having an annular flange 21 provided by the top portion thereof, with the lower portion of the cover depending within the container and the flange 21 seating on the shoulder 12 of the upper end structure 11. Preferably, a suitable sealing ring, such as a rubber ring or gasket 21' is provided disposed around cover 20 at the under side of flange 21 for engagement with and seating on shoulder or seat 12 of the container end structure 11, so as to tightly close and effectively seal the mouth end of the container with closure 20 secured and attached in closing position therein. The foregoing is more or less diagrammatically shown in Fig. 1 of the accompanying drawings, and will be readily understood by reference thereto.

For the purpose of tightly attaching the cover 20 in container closing position forced onto and held in sealing relation against the container end seat or shoulder 12, a fastening and locking member or bar 22, preferably

formed of a suitable spring metal, is pivotally mounted on the upper or outer side of cover 20 disposed diametrically thereof and thereacross with its ends extended a distance beyond the cover. The fastening bar 22 is mounted on the cover 20 by means of a pivot pin, such as the bolt 23 secured to and axially or centrally of the cover, with the bar swingably or rotatably mounted thereon. In accordance with one feature of the present invention, the upper side of cover 20 has a metal or other suitable material covering or plate 24 secured thereon and thereto with a raised portion or boss 25 formed thereon having an aperture therethrough. This boss 25 forms a space between the covering or plate 24 and cover 20, within which the bolt head 23' is disposed with the bolt extended outwardly through the aperture thereof and a nut or the like 23'' on the outer end thereof. The bolt head 23' can if desired be fixed and secured in position within boss 25 by the application of solder s, for example, within the boss around head 23' (see Fig. 1). The spring fastening bar 22 is loosely mounted on the outer end of bolt 23 for rotation thereon, and is retained in position thereon by nut 23'', with the boss 25 forming a bearing surface for the bar.

The outer, opposite ends of the fastening bar are preferably elevated, as by bowing the bar, and are adapted to be engaged with structure at the adjacent sides of the upper end of the container. The invention provides structure for engagement by the bar 22, and in the example hereof, such structure takes the form of a metal, or other material end or mouth ring 30, angular in cross section, fitted on the upper end of container end structure 11 with its inturned horizontal flange 31 fitting down on the end of structure 11, and with its cylindrical vertical flange 32 snugly and exteriorly fitting the outer surface of the container. This ring 30 is attached and secured to the container in any suitable manner against displacement.

At diametrically opposite sides of the ring 30, the upper, horizontal flange 31 thereof is formed with the slots or cut outs 33 through the inner edge of the flange and terminating inwardly a distance from the vertical exterior flange 32 (see Figs. 3 and 4). The upper end of the container end structure 11, in line with and below the ring slots 33 is cut out inwardly and downwardly to form the recesses 34, which are each extended at one end a distance beyond the adjacent end edge of the slot and under the upper vertical flange 31, but these extensions of the recesses 34 are formed at opposite ends of the respective diametrically opposite ring slots 33. The arrangement of slots 33 and recesses 34, is such that the fastening and locking bar is rotated to position with its opposite ends disposed above and alined with the ring slots 33, and

thereupon by bending or flexing the opposite bar ends downwardly through these slots 33 into recesses 34, the fastening bar can be rotated in the proper direction to move the ends thereof into recesses 33 under and engaged by the ring flanges, with bar 22 forcing and attaching cover 20 under pressure in container closing and sealing position.

In order to eliminate the possibility in the handling and use of these containers, of the fastening bars 22 thereof being accidentally or inadvertently swung or displaced from secured position in recesses 33 under ring flanges 31, the invention provides for positively locking the bar ends in fastened position. Referring now particularly to Figs. 3 and 4, the end of each ring slot 33 at which the recess 34 is extended under flange 31, has a portion of the flange bent downwardly to provide the depending projection or lip 35 terminating and spaced a distance from the bottom of recess 34 to permit the end of fastening bar 22 when sufficiently depressed to pass freely thereunder into the recess beneath ring flange 31. Thus, when the fastening bar ends are swung into the recesses 33 past the lips 35 and are released, they spring upwardly against ring flange 31 and are locked against lateral or swinging movements outwardly to slots 33, by these locking lips or projections 35 which engage and arrest movement of the bar. To release the cover 20 for removal the bar ends are depressed below lips 35, and the bar 22 rotated with the ends below and aligned with ring slots 33, respectively, whereupon release of the bar permits the ends to spring up through these slots and allows the removal of cover 20 to open the container.

While the form of the locking slots 33 and lips 35 here shown only provides the lips 35 and recesses 34 extended under the flange 31, at one and opposite ends, respectively, the invention contemplates and includes, where desired, the formation of the locking projections and recess extensions at both ends of each slot, in order to permit of movement of the bar 22 in either direction to lock the same and secure the cover 20 in closed position.

The design, construction and arrangement of the cover with the securing and locking mechanism therefor, is simple, practical and efficient, and eliminates and solves the disadvantages and difficulties encountered in attaching and removing the container covers and in providing for the efficient closing and sealing of the containers under all conditions of use and handling. The construction of mounting for the fastening bar 22 on the cover, with boss or elevated portion 25 of the cover plate 24, permits of properly positioning and locating the bar with respect to the locking slots and recesses in the container structure, while allowing the positioning of the cover below the upper end of the container and ring 30. A further advantage is in the

elimination of the necessity of extending the pivot pin or bolt 22 into and through any portion of the body of the cover 20, and thus eliminate reduction in the insulating efficiency of this cover. The end ring 30 of the metal angle form shown enables the provision by a single element in a practical manner, of both the locking slots and bar engaging lips or projections, with the ring providing the protection for the end of the container.

It is also evident that various changes, variations, modifications, and substitutions might be resorted to without departing from the spirit and scope of my invention, and hence I do not wish to limit myself to the exact and specific disclosures hereof.

What I claim is:

1. In a container, a mouth member at the upper end thereof having a depressed internal cover receiving shoulder, a ring member of angular cross section on the upper end of said mouth member having a horizontally disposed inwardly extending flange above the cover shoulder, the horizontal flange of said ring member formed with slots therethrough diametrically opposite, the portion of the mouth member beneath said slots recessed and extended at one end a distance under said flange, the recesses extended under the flange at the opposite end of each slot, respectively, and a portion of the flange at the end of each slot beyond which said recess extends bent downwardly to form a locking lip spaced a distance above the bottom of the recess.

2. In a container, a ring member having a horizontally disposed flange secured over the upper end of the container, said flange having a slot therein open through the inner edge thereof, and a portion of the flange at one end of the slot bent downwardly to provide a locking lip for engaging a fastening member carried by a cover.

3. In a container, a ring member secured over and around the upper end of the container, said ring member formed with a slot therein open through the inner edge thereof, the container end formed with a recess in the inner side thereof below said slot and extended at one end a distance under said ring member, the ring member formed at the end of the slot at which the recess is extended with a depending locking lip spaced a distance above the bottom of the recess, said lip adapted to engage a cover carried fastening member swung through said slot and moved inwardly of the recess under said ring.

4. In a container, in combination, a ring secured at the upper end of the container having a horizontally and inwardly disposed flange over the upper edge of the container, a cover receiving shoulder formed in the container below the upper end, the said ring flange having diametrically opposite slots therein open through the inner edge thereof, said flange at one end of each slot bent

downwardly to form a locking lip, said lips formed at opposite ends of said opposed slots, respectively, a cover seated on said container shoulder, and a fastening bar pivoted on said cover disposed diametrically thereacross with its ends extended beyond the cover and received in said ring slots, respectively, said fastening bar rotatable to swing the ends thereof under the locking lips beneath the ring flange in cover attaching position locked against displacement by said lips.

5. In a container, in combination, the upper end of the container formed with an internal depressed cover receiving shoulder there-around, a ring angular in cross section secured around the upper end of the container with the vertical flange thereof around the exterior of the container and the horizontal flange extending over and around the upper 15 end edge of the container, said horizontal ring flange formed with diametrically opposite slots therein open through the inner edge thereof, the container end formed with recesses below and opening into said ring slots, 20 respectively, each recess extended beyond one end of its ring slot a distance beneath the horizontal ring flange, the ring flange at the end of each slot under which the recess is extended bent downwardly to form a locking 25 lip spaced above the bottom of the recess, a 30 closure for the container seated on the inter-

nal shoulder of the container with its upper side below said ring slots, an elevated member on the upper side of the cover centrally thereof, and a spring material cover fastening bar pivotally mounted on said elevated member disposed diametrically of the cover with its ends extended beyond the cover, said bar depressible to lower the ends thereof through said ring slots for movement into 35 said recesses below the ring flange locked against lateral displacement by said locking lips.

6. In a container of the insulating type, a cover for the container comprising a body of insulating material, a plate member fixed on the upper side of said cover, an elevated boss formed in said plate centrally of the cover, a headed pivot member extending outwardly through said boss with the head of the member disposed between the boss and cover, a cover fastening bar rotatably mounted on said pivot member and supported on said boss, said fastening bar disposed diametrically across the cover, and means at opposite 40 sides of the container for locking engagement by said bar to releasably fasten the cover in closed position on the container.

Signed at Kennett Square, county of Chester, State of Pennsylvania, this 12th day of December, 1927.

HARRY R. CHANDLER.
